US00D542677S

(12) **United States Design Patent** (10) **Patent No.:** **US D542,677 S**
(45) **Date of Patent:** **** May 15, 2007**

(54) **THERMOSTAT HOUSING**

(75) Inventors: **Eric Barton**, Eden Prairie, MN (US);
Christian Trifilio, St.Paul, MN (US);
Paul Meyers, Fishers, IN (US)

(73) Assignee: **Honeywell International Inc.**,
Morristown, NJ (US)

(**) Term: **14 Years**

(21) Appl. No.: **29/247,444**

(22) Filed: **Jun. 19, 2006**

Related U.S. Application Data

(62) Division of application No. 29/224,346, filed on Feb. 28, 2005, now Pat. No. Des. 531,526.

(51) **LOC (8) Cl.** **10-04**

(52) **U.S. Cl.** **D10/50**

(58) **Field of Classification Search** D10/49-50;
236/46 R, 47, 49.3, 51, 84, 94; 400/485

Primary Examiner—Antoine D. Davis

(57) **CLAIM**

The ornamental design for a thermostat housing, as shown and described.

DESCRIPTION

FIG. 1 is a perspective view of a thermostat housing; FIG. 2 is a front elevation view of the thermostat housing of FIG. 1;

FIGS. 3-6 are left, bottom, right and top views of the thermostat housing of FIG. 1; and,

FIG. 7 is a front elevation view of another thermostat housing.

The broken line showing of portions of the housing are included for the purpose of illustrating broken lines and forms no part of the claimed design.

1 Claim, 7 Drawing Sheets
